UNITED STATES PATENT OFFICE.

ALEXANDER SELKIRK, OF ALBANY, NEW YORK, ASSIGNOR TO BURDICK & SON, OF SAME PLACE.

DESIGN FOR A FOUNDER'S CORE-SUPPORTING SHELL.

SPECIFICATION forming part of Design No. 32,319, dated March 6, 1900.

Application filed February 8, 1900. Serial No. 4,566. Term of patent 14 years.

To all whom it may concern:

Be it known that I, ALEXANDER SELKIRK, a citizen of the United States, residing at Albany, in the county of Albany and State of New York, have invented and produced a new and original Design for Founders' Core-Supporting Shells, of which the following is a specification, reference being had to the accompanying drawings, forming part thereof.

10 Figure 1 is a perspective view of a founder's core-supporting shell, showing my new design viewed from its outer side. Fig. 2 is a perspective view of the same viewed from its inner side. Fig. 3 is a view from its lower or 15 chambered side, and Fig. 4 is a cross-section.

As shown in the drawings, the leading and material features of my design consist in a shell having a shape or configuration comprising a rectangular top side portion A, having in it perforation *a* and a series of legs B, separated each from the other by corner-openings C and extending downwardly from the respective edges of said rectangular top side portion at right angles to the plane of the upper surface of the latter and terminating at 25 their lower ends in horizontally outwardly projected angular-shaped feet *b*, all disposed

and arranged as shown. The rectangular top side portion B has its upper surface flat and surrounding perforation *a*, as shown in Fig. 1, and the legs B have their respective outer surfaces also flat in both vertical and horizontal directions and terminating in plain flat feet *b*, having the plane of their lower sides parallel with the line of the plane of the upper side of the rectangular flat top side portion A. The openings C, separating said legs, occur at the corner portions of this shell and are extended downward from a point at a short distance below the line of union of legs B with the rectangular top side portion A and terminate at the point of union of said legs with the feet *b*, the said legs B being integral with both said rectangular upper side portion A and the said feet *b*, as shown.

Having described my invention, what I claim as new, and desire to secure by Letters Patent, is—

The design for a founder's core-supporting shell as herein shown and described.

ALEXANDER SELKIRK.
